United States Patent Office

Des. 221,884

Patented Sept. 14, 1971

221,884

COMBINED BOWL AND PLATE

Charles L. Seltz, Ann Arbor, Mich., assignor to King-
Seeley Thermos Company, Ann Arbor, Mich.

Filed July 6, 1970, Ser. No. 23,838

Term of patent 14 years

Int. Cl. D7—01
U.S. Cl. D44—15

FIG. 1 is a perspective view of a combined bowl and plate showing my new design;

FIG. 2 is an enlarged scale top plan view;

FIG. 3 is a front elevational view thereof;

FIG. 4 is a right side elevational view thereof;

FIG. 5 is a sectional view on line 5—5 of FIG. 2; and

FIG. 6 is a sectional view on line 6—6 of FIG. 2.

I claim:

The ornamental design for a combined bowl and plate, substantially as shown.
